BOAT PROPELLING AND STABILIZING APPARATUS

Adolph Ronning, Minneapolis, Minn.

Application May 9, 1938, Serial No. 206,817

8 Claims. (Cl. 115—35)

My invention relates to apparatus for the propulsion and stabilization of boats and water craft of various kinds.

The primary object of my invention is to provide a boat or ship propulsion apparatus or assembly wherein a plurality of separate propeller units are arranged in fore and aft and laterally spaced positions beneath the hull of the ship, and wherein each propeller unit is separately and independently driven to facilitate control of the movements of the ship.

Another object is to provide a propulsion apparatus of this character wherein fore and aft propeller units are arranged for oscillation about vertical axes to thereby vary the angles at which the thrust of the propellers is directed and enable the ship to be propelled forwardly, rearwardly, laterally or in any intermediate direction, to thus facilitate control of the ship and permit its being docked without the use of tugs, as required at present.

Another object is to provide a propulsion apparatus as described wherein a propeller unit is mounted at each side of the ship, substantially amidships, and spaced outwardly from the keel line. The propeller units are then arranged to be oscillated in vertical and fore and aft planes to thus tilt the propeller axes upwardly on one side of the ship and downwardly on the other side, or vice versa, whereby an upward thrust will be given to one side of the boat while a downward motion will be applied to the other side. As a result, the boat may be stabilized against the usual rolling motion encountered in heavy seas, and the normal downward roll of either side of the ship may be counteracted by an upward thrust on that side by proper positioning of the propeller units. The propeller units meanwhile add their bit to the forward driving motion of the ship to keep it on its course.

Another object is to provide control means for actuating and manipulating the propellers in the manner described for stabilizing the ship, and which control means accomplishes this operation entirely automatically under influence of the normal rolling movements of the ship, in order thus to compensate properly for these movements and prevent undue rolling of the ship in even the heaviest seas.

Another object is to provide means for adjusting the axis of rotation of the fore and aft propeller units, not only about a vertical axis as described, but also in a vertical plane whereby they may be tipped upwardly or downwardly to exert their thrust angularly and so to stabilize the

ship in a fore and aft direction and prevent the so called pitching of the ship. Thus the aft propeller may be adjusted to bring about a downward, as well as forward, thrust when the ship's stern has a tendency to rise, and vice versa. The forward or fore propeller unit effects a similar but opposite result in order to hold the bow of the ship in proper line.

A further object is to provide an effective means for rotating the fore and aft propellers about their vertical axes to thus provide for steering the boat, and which steering means may be remotely controlled from the bridge or other steering station in the ship.

A further object is to provide a novel and advantageous form of propeller mounting in which each propeller is mounted in and depended from its individual caisson or bell which is in turn mounted in a well or housing formed in the bottom of the ship so that said propeller depends below the ship bottom to enter the water. These caissons are then arranged to be oscillated or tipped in vertical planes to bring about the aforesaid angle control of the thrust direction, and the caissons are furthermore so arranged as to be readily removable from their wells for repairing any of the propellers without moving the ship into dry dock.

A further object is to provide a propulsion apparatus for ships and which employs a plurality of propellers as described, and in which each propeller may be conveniently powered or driven by its individual drive unit, engine, or motor so that any one or more of these propeller assemblies may be taken out of commission for repairs or other purposes without seriously disabling the ship.

Still another object is to provide automatically operating means for indicating, at a remote point such as the bridge, the angular position in which the steering or fore and aft propellers are operating, to thus facilitate the steering and control of the ship.

Still a further object of the invention is to provide a ship propulsion apparatus of the foregoing characteristics in which certain of the propellers may be mounted in recesses or openings cut in the keel of the ship in such manner that the keel will serve as protection for the propellers against obstructions in the water.

The foregoing and other objects, together with means whereby the same may be carried into effect, will best be understood from the following description of my invention, reference being had

therein to the accompanying drawings, wherein:

Fig. 1 is a side elevation of a ship equipped with my propulsion and stabilization apparatus.

Fig. 2 is a fragmentary, longitudinal, enlarged and vertical section through either the fore or aft propeller assemblies shown in Fig. 1.

Fig. 3 is a vertical, transverse section along the line 3-3 in Fig. 2.

Fig. 4 is an enlarged, longitudinal, vertical section through one of the amidships propeller assemblies, shown in Fig. 1.

Fig. 5 is a transverse, vertical section along the line 5-5 in Fig. 4.

Fig. 6 is a view similar to Fig. 1, showing a modified arrangement or mounting for the propeller assemblies.

Fig. 7 is an enlarged, fragmentary, transverse and vertical section along the line 7-7 in Fig. 6.

Fig. 8 is an enlarged, fragmentary, transverse and vertical section along the line 8-8 in Fig. 6.

Fig. 9 is a fragmentary, sectional view along the irregular line 9-9 in Fig. 8.

Fig. 10 is an enlarged, horizontal and diametrical section along the line 10-10 in Fig. 7.

Referring now more particularly to Figs. 1 through 5 of the drawings, the reference character A designates a ship or boat which may be of any size, style, or type, and in connection with which I employ the propeller assemblies or units designated generally at B, C, D, and E, which are, of course, of a size commensurate with the size of the ship A. These propeller assemblies are arranged, in the particular construction shown, with one located near the rear of the boat, one near the bow, and two in transverse alignment substantially amidships, but it is to be understood that additional assemblies may be used if found desirable. The propeller assemblies are hereinafter referred to as the aft steering assembly B, the fore steering assembly C, and the midship balancing or stabilizing assemblies D and E.

The ship A has the usual hull F of suitable construction, the upper or deck structure G, and the longitudinally and centrally extended keel K along its bottom. The aft propeller assembly will be first described, and the same comprises the propeller head or blade unit 10 and the drive unit or motor 11 which is supported above the blade unit and above the tubular standard 12. It may here be noted that the blade unit or propeller head 10, together with its transmission housing 13 and guard 14, are of the type disclosed and claimed in my copending application for United States patent on boat propulsion apparatus Serial No. 204,061, filed April 25th, 1938, and to which reference is invited for details of this assembly. It is sufficient to set forth herein that the propeller unit comprises a frontal propeller 15 and rear propeller 16, each of which includes a water confining guard rim 17, and which are driven in either the same or opposite directions by suitable transmission gears (not shown) in the housing 13, and by the drive shaft 18 which depends from the drive unit 11 downwardly through the standard 12. The advantages of this specific propeller arrangement set out in the application above identified make it well suited for use in the present apparatus, but it will, of course, be understood that any other suitable propeller may be used as desired.

The ship's hull F is provided with a well or housing 19 which extends some distance above

the water line of the ship, and is located in the aft part of the hull at the center thereof. This well 19 has the upper portion or wall 20, and the curved lower end 21 which has the longitudinally elongated central opening 22. The keel K has a rectangular opening 23 cut below the well 19, and these two openings 22 and 23 communicate as shown. The propeller unit is mounted in a caisson or bell housing 24 which is of smaller diameter than the well 19, and has a rounded lower end 25 which may rest against the rounded lower end 21 of the well. The standard 12 is mounted and journaled vertically through the rounded lower end 25 of the caisson 24, and is retained in place by a water tight gland assembly 26. The propeller unit 10 thus depends into the opening 23 in the keel K, which affords sufficient clearance for the unit, and the drive unit 11 is supported within the caisson so that it is protected from the water. It will be noted that the water may penetrate and enter the well 19 around the caisson 24 through the opening 22, but this is of no disadvantage since the water will not rise above the open upper end of the well and cannot reach any working or driving parts within the caisson. The upper end of the caisson may be open, as shown, to facilitate repair or inspection of the drive unit 11 and other parts therein.

The caisson 24 is retained in place in the well 19 by trunnion pins 27 which are located in transverse alignment, and on the center from which the radii of the rounded ends 21 and 25 are determined. It will be noted that these ends are rounded only in a fore and aft direction, and transversely they are only slightly curved to blend nicely into the contour of the hull F. The trunnion pins 27 are screwed inwardly through tubular members 28 secured to the side walls of the well 19, and their inner ends enter sockets 29 on the sides of the caisson so that the pins will serve as bearings on which the caissons may oscillate or rock, but in such manner that water cannot enter around the pins.

Normally these pins 27 will retain the caisson in the well, but by unscrewing them until they clear the sockets 29, the caisson is freed and may be lifted out of the well 19 by the ship's boom or other lifting device. It is thus possible to entirely remove the drive and propeller assembly for repair or replacement without dry docking the ship.

The clearance 30 afforded between the upper wall portions of the well 19 and caisson permits the caisson to be oscillated or rocked in a vertical plane and in a fore and aft direction about an axis defined by the trunnion pins 27, and this action may be carried out automatically and mechanically by a means now to be described. It will be evident that no lateral movement of the caisson is desired or possible, and for this reason the side walls of the caisson and well 19 has a relatively tight but slidably fit, as clearly shown in Fig. 3.

Hydraulic cylinders 31 and 32 are secured to both front and rear walls of the well 19, and have plungers or rams 33 and 34 which extend slidably into the interior of the well through openings in the walls in line with the bores of the said cylinders. These plungers 33 and 34 carry rollers 35 at their inner ends which bear against the adjacent front and rear walls of the caisson 24 in such manner as to exert a pressure on the caisson in horizontal planes, and near its upper end,

when hydraulic pressure is applied to the plungers. For this purpose a pump or pressure unit 36 is provided, and is connected by pipes or lines 37 and 38 to the cylinders 31 and 32 in such manner that, as the pump operates in one direction, pressure will be applied to one cylinder while, as the pump direction is reversed, pressure will be applied to the opposite cylinder. A reversible electric motor 39 is employed for operating the pump 36, and this motor is controlled by a mercury switch unit 40 connected between the motor and its energizing source 41 so that in one position of the switch the motor will rotate in one direction, while in another position the motor will be reversed.

The drive unit 11 may be an electric motor, as shown, or may be a combustion engine of any kind, as may be desired. In the latter case the exhaust gases, cooling water, and other waste products may be very efficiently discharged or exhausted through or near the axis of rotation of the propellers 15 and 16, by any of the structures set out in my hereinbefore identified copending application, as well as another of my applications, Serial No. 202,258, which was filed April 15th, 1938. Reference is invited to these two applications for details as to the exhaust means. The drive unit 11 is rigidly supported in the caisson 24 by brackets 42 secured to its side walls, and is connected by a coupling 43 to the aforesaid drive shaft 18. However, the standard 12, and of course the shaft 18 and connected propeller head 10, are all journaled for rotation about a vertical axis through the lower end of the caisson, as clearly shown. A large worm gear 44 is secured to the upper portion of the standard 12, and is engaged by a worm pinion 45 which is journaled in a bracket 46 secured to the caisson wall and is driven by a reversible electric steering motor 47. A transversely extended bracket 48 secured within the caisson 24 serves as a bearing support for the gear 44 and standard 12 to prevent axial displacement of the latter, and also has an extended arm 49 which rigidly supports the steering motor 47. This motor may be controlled by a reversing switch (not shown), from any remote point such as the bridge or control room of the ship.

In operation, and with the ship riding at an even keel and moving forwardly, the propeller assembly B stands in the position shown in the drawings and, as the propellers 15 and 16 rotate, they drive the ship forwardly as will be understood. Now, should it be desired to drive the ship laterally, rearwardly, or to any intermediate angle, the steering motor 47 is operated from the bridge or other remote control point, to rotate the standard 12 about its vertical axis and turn the propeller unit 10 to the desired direction upon which the thrust of the propellers 15 and 16 is exerted in the selected direction. It is thus possible to steer the ship without the usual rudder, or in connection therewith, and also to navigate the ship in any direction for docking or other purposes.

The mercury switch 40 is so located and arranged that, as the ship tilts or pitches forwardly, tending to raise its stern from the water, the motor 39 will be automatically energized, causing it to rotate the pump 36 and set up a hydraulic pressure in the rear cylinder 32. This action urges the rear plunger 34 forwardly, causing it to push the caisson 24 and rock or tilt the same forwardly at its upper end. As a result, the propeller unit 10 is tipped or rocked to a forwardly and downwardly inclined position so that it will

exert a downward pull upon the stern of the ship and overcome this tendency of the stern to rise. Should the stern have a tendency to settle in the water the mercury switch 40 automatically reverses the motor 39, causing a pressure to be set up in the frontal or forward cylinder 31 and urging the plunger 33 rearwardly to so rock the caisson 24 that the axis of rotation of the propellers 15 and 16 will be tipped upwardly in a forward direction. An upward motion is thus imparted to the ship's stern, overcoming its tendency to settle. The aforesaid upward and downward thrusts of the propellers, when thus rocked on their axes in a vertical plane is, of course, in addition to their normal straightaway driving thrust so that the ship is maintained on its course. The mercury switch 40 is thus seen to be responsive to rocking or pitching motion of the ship about its longitudinal axes, and serves to so control the motor and pump assembly that this pitching motion will be, in great part at least, eliminated, and the ship will be much more stable in even the heaviest seas.

The frontal or fore steering propeller assembly C is identical in construction and operation to the aft assembly just described, with the single exception that the mercury switch controlling its pump and motor is oppositely set so that it rocks the frontal propeller unit upwardly at its forward end, while the rear propeller unit is being rocked downwardly at its forward end. As a result the normal depression or dipping motion of the bow of the ship, as its stern rises, will be compensated for by the frontal or fore propeller unit, and the propellers thus work in unison at all times to stabilize the ship against pitching action. This fore propeller assembly C also aids in the steering of the ship, and may be independently controlled for this purpose if so desired. In fact such independent control, either at all times or selectively, would be of advantage in maneuvering the ship since either end could be moved in any desired direction.

The keel K will act as guards for the fore and aft propeller units B and C, since they are located in openings formed in the keel, and the propellers will thus be protected from obstructions in the water. This arrangement has the further advantage of reducing the draft of the boat since no projections whatever are formed below the keel.

The midship balancing or stabilizing propeller assemblies D and E are each identical in construction, and are quite similar to the aft assembly B so that only the major parts need be described. These assemblies D and E are arranged midships, or substantially so, in transverse alignment, and are spaced outwardly some distance from the keel K. These assemblies comprise the wells 50-51 which have their rounded lower ends 52-53 opening out beneath the ship through the fore and aft elongated openings 54-55. The caissons 56-57 are mounted by their rounded lower ends 58-59 in the wells, and carry the drive units 60-61 which are supported within the caissons atop the standards 62-63. These standards are, in this case, rigidly secured to and through the bottoms of the caissons and carry the propeller units 64-65 without any provision for rotation about a vertical axis. The units 64-65 are thus so arranged that they drive the ship forwardly at all times but, if desired, they may be arranged for reversing when the ship is moving rearwardly and may be completely disabled or dis-

connected when the ship is being moved to either side.

The caissons 56—57 are rockably mounted in the wells 50—51 upon trunnion pins 66—67—68, the outer two of which are extended inwardly through the outer walls of the wells, while the center one penetrates the single parting wall of the well, as here shown, and supports both caissons at that point. Otherwise the construction and arrangement of these pins is identical with the pins 27 hereinbefore described. However, the wells 50—51 might in actual practice be spaced substantially apart, in which case a pair of trunnion pins would be employed for each caisson.

The caissons 56—57 are thus so arranged that they may be rocked in a vertical and fore and aft extended plane on their trunnion pins, and each may move independently of the other. In actual use the caissons are always oppositely moved, and this action is automatically brought about by means now to be described.

Hydraulic cylinders 69—70 are mounted in the front and rear walls of both wells 50—51, and plungers 71—72 are slidably mounted in the cylinders with their inner roller ends in contact with the front and rear walls of the caissons 56—57 near their upper ends. A pump or hydraulic pressure unit 73 is provided, and is connected by lines 74—75 to the frontal cylinders 69, while the rear cylinders 70 are cross connected by a line 76. A reversible electric motor 77 is connected to the pump 73, and is controlled by a mercury switch unit 78 connected between the pump and its electrical source of supply 79.

The switch unit 78 is so arranged that should the ship roll or tilt downwardly on the left hand, or port, side, the motor 77 will be operated to rotate the pump 73 and cause pressure to be exerted against the plunger 71 on the frontal left side. The left hand or port caisson 56 will thus be rocked rearwardly, causing the propeller unit 64 to tilt upwardly and forwardly, as shown in Fig. 4. The pressure in the rear port cylinder 70 caused by rearward motion of the plunger 72, will cause a forward pressure to be exerted (through the line 76) on the right hand or starboard rear plunger so that the starboard caisson 57 will be rocked forwardly, and the forward end of its propeller unit 65 will be moved downwardly, also as shown in Fig. 4. The result of this action is to cause an upward motion or force to be applied on the port side, while a downward motion is applied to the starboard side to thus compensate for, and prevent, this roll to port which would otherwise occur. Then should the ship start to roll to the starboard side, the caissons will be rocked in the opposite direction by reversal of the motor 77 by the switch 78, and an upward force will be applied in a starboard side while a downward force is applied to the port side to prevent this roll. The mercury switch is thus responsive to rolling or transverse tipping motion of the ship, and the ship is now stabilized against both fore and aft and transverse motions in the sea.

The propeller assemblies D and E are preferably spaced outwardly from the keel K some distance, as shown, in order that they may exert a maximum leverage on the ship to prevent said rolling motion.

Referring now to Figs. 6 through 10 of the drawings, it will be seen that I have provided a modified construction in which all of the pro-

peller assemblies B', C', D', and E' are rigidly mounted in the ship A' insofar as any tilting or rocking motion is concerned. In other particulars the construction and arrangement is quite similar to that hereinbefore described, and the aft steering assemblies B' will be first described in detail.

This assembly B' comprises the propeller or blade unit 10^a, drive unit 11^a, and standard 12^a arranged exactly as hereinbefore described. The hull F' has a well 19^a formed in its after, central portion, and this well has the open lower end 22^a communicating with an opening 23^a cut in the keel K'. A caisson 24^a is mounted in the well 19^a and is retained therein by an outwardly turned flange 80 on its upper end which overhangs the upper edge of the well. The standard 12^a is journaled vertically through the bottom 25^a of the caisson 24^a through the watertight gland 26^a so that the propeller unit 10^a depends into the opening 23^a in the keel while the drive unit 11^a is protected within the caisson.

A worm gear 44^a is affixed to the standard 12^a within the caisson and bears against a transverse bearing bracket 48^a while a worm pinion 45^a meshes with the gear and is driven in either direction by a reversible steering motor 47^a so that the propeller unit 10^a may be rotated about a vertical axis for steering the ship, as aforesaid.

In order to indicate to the operator of the steering controls the exact angular position of the propeller unit 10^a, I provide the indicator mechanism 81. This may be of a well known type in which a metal member is moved through a magnetic field to thereby cause a variation in a current flowing in a circuit including a meter which is calibrated to indicate the position of the metal member. Therefore, a cam 82 is mounted on the standard 12^a to turn therewith and engages the metal field member 83 to move the same toward or away from the standard as the same rotates. The meter 84 is located in any desired remote point in the battery or energizing circuit 85, and, as the standard rotates and moves the member 83, the meter reading will be correspondingly varied. The meter may then be calibrated to read in angular directions between forwardly and rearwardly positions of the propeller unit 10^a, and so indicate exactly and at all times the position thereof. This indicating means may also be used in all of the propeller assemblies B, C, and C' as well, and adds considerably to the flexibility of operation and makes it possible for the pilot or operator to so set the propellers at a slight angle to compensate for drift in currents running transversely to the direction of travel of the ship.

The forward propeller assembly C' is identical with that just described, and needs no further description herein.

The midships propeller assemblies D' and E' are identical in construction and arrangement, and include the caissons 56^a—57^a mounted in the transversely aligned wells 50^a—51^a and carrying the drive units 60^a—61^a, the propeller or blade units 64^a—65^a and connecting standards 62^a—63^a, which in this case are rigidly mounted through the bottoms 58^a—59^a of the caissons. The caissons 56^a—57^a are removable from the wells, being in this case provided with hooks 86 for this purpose, and the bottoms 58^a—59^a are shaped to fit nicely into the contour of the bottom of the hull F'. The keel K' carries stop plates 87 which engage the inner and lower edges 88 of the caissons.

son bottoms, and so retain the caissons in place in the wells 50°—51°. The caissons are further retained in place and prevented from vibrating by set screws 89 which are threaded through the walls, and may be adjusted to bear outwardly against the walls of the wells, as shown.

The above structure operates exactly as does that described hereinbefore in some detail, and no further description should be required herein. 10 It is understood that I may make variations in the specific structures herein described, so long as such variations fall within the spirit and scope of the appended claims. Having now therefore fully disclosed my invention, what I claim as new 15 and desire to secure by Letters Patent, is:

1. An apparatus for propelling and stabilizing a ship, comprising a well formed in the ship and opening downwardly therebeneath, a caisson member removably mounted in the well and supported 20 for oscillation in a vertical and fore and aft plane therein, means operable against the sides of the caisson member for oscillating it within the wells, and a propeller unit mounted in the caisson member and having its blade device depended below the well.

2. An apparatus for propelling and stabilizing a ship, comprising a well opening downwardly through the hull of the ship and over the keel thereof, the said keel having an opening, a caisson member mounted in the well and upwardly removable therefrom, means for retaining the caisson against downward displacement from the well, a propeller unit rotatably mounted vertically through the bottom of the caisson member and having its blade device extended into the opening in the keel, and means for rotating the propeller unit about its vertical axis whereby the horizontal angle of thrust may be varied for steering the ship.

3. An apparatus for propelling and stabilizing a ship, comprising a well opening downwardly through the hull of the ship and over the keel thereof, the said keel having an opening, a caisson member mounted in the well and upwardly removable therefrom, means for retaining the caisson against downward displacement from the well, a propeller unit rotatably mounted vertically through the bottom of the caisson member and having its blade device extended into the opening in the keel, means for rotating the propeller unit about its vertical axis whereby the horizontal angle of thrust may be varied for steering the ship, and means for visually and remotely indicating the relative angular position of the propeller unit about its vertical axis.

4. An apparatus for propelling and stabilizing a ship, comprising a well formed in the ship and opening downwardly through the bottom thereof, a caisson member oscillatably supported in the well with bearing engagement with the bottom thereof, the said well and caisson member having straight sides parallel with the plane in which said member oscillates, means operable on the other walls of the caisson member for os-

cillating the member, and a propeller unit suspended in and through the caisson member.

5. In an apparatus for stabilizing a ship, the same including a housing opening downwardly through the hull, a caisson member mounted in the housing for rocking movement about a substantially horizontal axis, a propeller unit rotatably mounted on a substantially vertical axis through the bottom of the caisson member and having its blade device suspended beneath the downwardly opening end of the housing, means for rotating the propeller unit about its vertical axis for steering and propelling the ship, and means operable against opposite sides of the caisson member for rocking the same about said horizontal axis.

6. In an apparatus for stabilizing a ship, the same including a housing opening downwardly through the hull, a caisson member mounted in the housing for rocking movement about a substantially horizontal axis, a propeller unit rotatably mounted on a substantially vertical axis through the bottom of the caisson member and having its blade device suspended beneath the downwardly opening end of the housing, means for rotating the propeller unit about its vertical axis for steering and propelling the ship, hydraulic means operable against opposite sides of the caisson member for rocking the same about a horizontal axis, and said hydraulic means including an automatic control for rocking the caisson member in accordance with the inclination of the ship.

7. Apparatus for propelling and stabilizing a ship of the type having a hull and longitudinal, 35 centrally located and depended keel, comprising housings at front and rear portions of the ship opening downwardly therethrough immediately over the keel, the said keel having openings below said housings, caisson members mounted in the housings and supported for rocking movement therein about transverse axes, propeller units mounted in the caisson members and having their blade devices depended into the openings in the keel, and automatically controlled 40 means for rocking said caisson members about transverse axes for varying the angle of thrust of the blade devices.

8. Apparatus for propelling and stabilizing a ship of the type having a hull and longitudinal, 50 centrally located and depended keel, comprising housings at front and rear portions of the ship opening downwardly therethrough immediately over the keel, the said keel having openings below said housings, caisson members mounted in the housings and supported for rocking movement therein about transverse axes, propeller units mounted in the caisson members and having their blade devices depended into the openings in the keel, means for adjusting the blade devices about upright axes for steering the ship, and automatically controlled means for rocking said caisson members about transverse axes for varying the angle of thrust of the blade devices.

ADOLPH RONNING. 65
